APPARATUS FOR GRINDING THE EDGES OF
GLASS SHEETS

William Owen, Pittsburgh, Pa., assignor to Pittsburgh Plate Glass Company, a corporation of Pennsylvania

Application November 23, 1933, Serial No. 699,399

4 Claims. (Cl. 51—40)

The invention relates to apparatus for grinding the edges of glass sheets, such as those employed as windshields, and is of particular advantage in those cases in which one or more of the edges of the sheet are curved. The apparatus is designed to grind or "edge" a plurality of sheets and two edges of each sheet at one time, thus increasing its capacity and reducing the labor cost. The invention has for its objects the provision of simple relatively cheap apparatus, which occupies a minimum of floor space; which can be easily operated to capacity by only two men; and in which the grinding pressure can be adjusted to just the right degree to give the best results irrespective of the size and weight of the grinding wheels. One embodiment of the invention is illustrated in the accompanying drawings, wherein:

Figure 1 is a side elevation. Fig. 2 is a section on the line II—II of Fig. 1. Fig. 3 is an enlarged sectional view. And Figs. 4 and 5 are detail views, Fig. 4 being a side elevation and Fig. 5 a section on the line V—V of Fig. 4.

Referring to the drawings, Fig. 1 shows two of the machines side by side, the machine marked A being arranged for grinding the long edges of a set of windshields, and the machine marked B being arranged to grind the short edges of a set of windshields. The two machines are, aside from their adjustment, the same throughout so that a description of one will apply equally well to the other and reference will be had particularly to the machine B. The machine comprises a frame in the form of a pair of vertical channels 1, 1 seated at their lower ends upon the floor and attached at their upper ends to the channel 2 which forms a part of the building in which the machine is located. Guided for vertical movement on the channels 1, 1 is a transverse beam 3 provided with guide members 4, 4 at the ends carrying wheels 5, 5 which engage the channels. In order to raise and lower the beam, a screw 6 is employed extending through a nut 7 carried by the beam 3 and keyed at its upper end to a worm wheel 8 which is suitably swivelled on the beam 2. This worm wheel is driven by a worm operated from the electric motor 9.

The beam 3 consists of a pair of channels 10, 10 (Fig. 2) and on this beam is mounted a pair of cross heads, each comprising a U-shaped frame 11 carrying pins 12, which are supported by the flanges of the channels. Pivoted mounted on each of the cross heads is a depending arm 13 and these arms are yieldingly pulled toward each other by means of a pair of rods 14, 14 pivoted

at their outer ends to the arms 13, 13 and connected at their inner ends by means of a coil spring 15.

Carried by the lower end of each arm 13, 13 is a frame 16, on which is mounted an electric motor 17 driving through suitable reduction gearing a grooved grinding wheel 18. As indicated in Fig. 3, eight grooves are provided in each wheel so that eight windshields may be edged or ground at one time, the curvature of the grooves in the grinding wheels being such as to give the desired round effect upon the edges of the windshields. These windshields 19, 19, 19, etc. are illustrated as consisting of laminated safety glass, as the machine is primarily designed for edging this type of glass, but it will be understood that the apparatus may be employed for edging sheets of ordinary windshield glass. Each of the frames 16, which carries the motor and grinding wheel, is provided with a bracket 20 carrying a roller 21 and these rollers are adapted to engage a pair of templets 22, 22 carried by the table which supports the windshields to be edged.

In the operation of edging the windshields by moving the grinding wheels vertically, the spring 15 pulls the arms 13, 13 toward each other so as to cause the wheels to engage the edges of the windshields and the relation of the templets and guide rollers with respect to the edge of the wheels is such that during the movement of the grinding wheels past the edges of the windshields, just the right amount of glass will be removed in order to insure properly rounded edges at the ends of the windshields.

The table 23, which is located midway between the beams 1, 1, is provided with a pair of seats 24, 24 (Fig. 2) for supporting two sets of windshields so that while one set of shields is being edged, another set is being assembled and clamped in position upon the other seat, and the table is mounted for movement along a track 25 so that the seats 24, 24 may be shifted back and forth from the central grinding position shown in Fig. 2 to the side positions C and D, as indicated in such figure. The seats 24, 24 include plates 26 of hard rubber which are grooved, as indicated at 27 in Fig. 5, to support and space the edges of the windshields 19; and in opposition to these sheets is a clamping plate 28 also of hard rubber grooved similarly to the plate 26 and serving to support and space the upper edges of the windshields. The clamping plate is pulled down in position at each end by means of a pair of rods 29 and 30 with an interposed spring 31, as indicated in Fig. 4. The rod 30 is pivoted at its 110

lower end to the plate 26, while the rod 29 is provided at its upper end with a knobbed handle 32, adapted to fit into a curved recess in the plate 28. A slot 33 extends from the curved recess to the end of the plate, permitting the ready application and release of the clamping device.

In operation, the rotation of the screw 6 from the motor 9 causes the beam 3 and grinding devices carried thereby to move down past the ends 10 of the windshields so that the grooved grinding wheels act thereon and round them, as indicated in Fig. 3, the grinding wheels finally arriving at a position below the table which carries the windshields. The movement of the parts is preferably 15 stopped at this point by automatic means. Such automatic means preferably includes a rod 34 slidably mounted in brackets 35, 35 carried by one of the beams 1, and provided with a pair of adjustable stops 36, 36. The ends of the rod 34 20 are adapted to operate a pair of limit switches 37, 37 whose operating arms are in the line of movement of the ends of the rod. When the downward grinding movement of the apparatus is completed, a stop member 38, carried by the 25 arm 4, engages the lower stop member 36 moving the rod down and opening the limit switch 37. The opening of this switch cuts off the supply of current to the motor 9 and also to the motors 17 which rotate the grinding wheels. The table 30, 23 is now shifted so as to bring another set of windshields into position for grinding, and on starting the motors 9 and 17 by means of a suitable push button arrangement, the motors are reversed, and the beam 3 moved upward so that 35 the new set of windshields is edged on the upward movement of the grinding wheels. This arrangement for grinding on both the down and up movement of the grinding wheels in connection with the use of the table having the two seats for 40 handling two sets of windshields, reduces the time lost in operating the machine and increases its capacity materially.

Provision is made for adjusting the cross heads carrying the arms 13, 13 toward and from each 45 other to take care of work of different size by the use of a pair of adjusting screws 39 which are threaded through nuts carried by the cross heads and are suitably swiveled against endwise movement in the beam 3. Each of these screws is provided with an operating wheel 40, over which 50 passes a sprocket chain 41, by means of which the operator can adjust the cross heads toward and from each other. When the apparatus is used for edging the sheets lengthwise thereof, the arms 55 13, 13 are adjusted to the position shown in machine A, and the windshields 19 are supported in the position shown upon a table 42 similar to the table 23 except in the matter of height. In this case, one of the templets 43 is curved in 60 order to cause the grinding wheel to follow the proper path to edge the curved sides of the windshields. The operation in this case is the same as that heretofore described, machine A being employed for edging the long sides of the wind- 65 shield, and machine B being employed for edging the short sides.

What I claim is:

1. In combination in apparatus for edging glass plates, an upright guide frame, a beam mounted 70 for vertical movement in the frame, a pair of

cross heads carried by the beam and adjustable therealong, a pair of depending arms pivoted to the cross heads at their upper ends, a grooved grinding wheel and driving motor therefor carried by the lower end of each arm, means for yieldingly pulling the two arms toward each other, a table located between the arms, means for supporting a glass plate to be edged in a vertical position upon the table, a pair of templets carried by the table, means movable vertically with each of the grinding wheels for engaging one of the templets, and means for raising and lowering said beam.

2. In combination in apparatus for edging glass plates, an upright guide frame, a beam mounted for vertical movement in the frame, a pair of cross heads carried by the beam and adjustable therealong, a pair of depending arms pivoted to the cross heads at their upper ends, a multiple grooved grinding wheel and driving motor therefor carried by the lower end of each arm, means for yieldingly pulling the two arms toward each other, a table located between the arms, means for supporting a plurality of glass plates to be edged in vertical positions upon the table, a pair of templets carried by the table, means movable vertically with each of the grinding wheels for engaging the templets, and means for raising and lowering said beam.

3. In combination in apparatus for edging glass plates, an upright guide frame, a beam mounted for vertical movement in the frame, a pair of cross heads carried by the beam and adjustable therealong, a pair of depending arms pivoted to the cross heads at their upper ends, a multiple grooved grinding wheel and driving motor therefor carried by the lower end of each arm, means for yieldingly pulling the two arms toward each other, a track at the lower end of the guide frame extending transversely of said beam, a table mounted for movement along the track and provided with two spaced supporting seats, means for clamping a plurality of glass plates to be edged in a vertical position on each of said seats, a pair of templets carried by said table on the opposite sides of each of said seats, guide means movable vertically with each of said grinding wheels for engaging the templets when one of said seats is positioned midway between the arms, and means for raising and lowering said beam.

4. In combination in apparatus for edging glass plates, an upright guide frame, a beam mounted for vertical movement in the frame, a pair of cross heads carried by the beam and adjustable therealong, a pair of depending arms pivoted to the cross heads at their upper ends, a multiple grooved grinding wheel and driving motor therefor carried by the lower end of each arm, means for yieldingly pulling the two arms toward each other, a table located between the arms, means for supporting a plurality of glass plates to be edged in vertical positions upon the table, a pair of templets carried by the table, means movable vertically with each of the grinding wheels for engaging the templets, a vertical threaded shaft for raising and lowering said beam, and a motor for driving said shaft.

WILLIAM OWEN.
